United States Patent Office.

JOHN YOUNG, OF AMSTERDAM, NEW YORK.

Letters Patent No. 88,110, dated March 23, 1869.

IMPROVED CLOTHES-WRINGER.

The Schedule referred to in these Letters Patent and making part of the same.

To all whom it may concern:

Be it known that I, JOHN YOUNG, of Amsterdam, in the county of Montgomery, and State of New York, have invented a new and useful Improvement in Clothes-Wringers; and I do hereby declare that the following is a full, clear, and exact description of the construction and operation of the same, reference being had to the annexed drawings, making a part of this specification, in which—

Figure 1 is a vertical side view of my invention, and

Figure 2 is a front elevation of the same.

The object of this invention is to simplify the construction of clamps, or jaws for clothes-wringers, and also to attach the same more readily and securely to the wash-tub, &c.

The nature of this invention will be more fully understood by the following description.

A, figs. 1 and 2, represents the standard, or upright of a clothes-wringer.

b and c are cross-bars, which hold the two standards A together.

I form a strip of metal, D, nearly as shown in the drawing, figs. 1 and 2, and secure one end, by means of screws, to the standard A. The other portion of said metal strip D, is suitably secured to the jaw E.

A thumb-screw, f, in general use for the purpose, is

inserted through the jaw E, into a nut secured in the standard.

A cross-bar, G, connects the two jaws E, and holds them tolerably rigid with relation to each other.

It will be observed, that when the jaw E is compressed, or drawn toward the standard A, the action produces a flexure of the metallic strip D, and which, by its elasticity, regains its required position upon the removal of said pressure.

These clamps are more easily constructed than the ordinary hinged or jointed ones, and are believed to be more durable than those heretofore used.

I am aware that the clamping-bar has been fastened to the wringer-post, to allow a lateral play, as in patent of George B. Griffin, June 4, 1861, and this I do not claim; but,

What I do claim, is—

Connecting the clamping-bar E to the wringer-post, by a metallic spring-fastening, in such a way that the spring throws the clamping-bar off from the post, when released from pressure.

JOHN YOUNG.
